UNITED STATES PATENT OFFICE

CHARLES LE G. FORTESCUE, OF WILKINSBURG, PENNSYLVANIA, ASSIGNOR
TO WESTINGHOUSE ELECTRIC & MANUFACTURING COMPANY, A COR-
PORATION OF PENNSYLVANIA.

REACTANCE-COIL.

No. 851,658.

Specification of Letters Patent.

Patented April 30, 1907.

Application filed March 23, 1906. Serial No. 307,732.

To all whom it may concern:

Be it known that I, CHARLES LE G. FORTESCUE, a subject of the King of Great Britain, and a resident of Wilkinsburg, in the county of Allegheny and State of Pennsylvania, have invented a new and useful Improvement in Reactance-Coils, of which the following is a specification.

My invention relates to electric apparatus and it has for its object to provide transformers or reactance coils which shall be adapted for use in connection with poly-phase electric circuits and shall embody a specially advantageous and symmetrical design.

It is often desirable to use transformers and reactance coils in connection with rotary converters or for similar purposes and I provide, according to my present invention, a coil group which comprises in general, magnetizable core members which are symmetrically disposed and are supported by a non-magnetizable frame structure and means for magnetically interconnecting the several core members. The aforesaid non-magnetizable supporting frame may be relatively light since all the electromagnetic stresses are balanced by reason of the symmetrical distribution of the flux.

A further advantage of my improved coil group lies in the fact that the inductance may readily be adjusted without disturbing the symmetry of the arrangement.

In the accompanying drawings, Figure 1 is a plan view, of a reactance coil group which is adapted for use with three-phase alternating current circuits and which is constructed in accordance with my invention, certain of the parts being broken away to more fully disclose the structure. Fig. 2 is a view, partially in elevation and partially in section, of the group shown in Fig. 1.

Referring to the drawings, the device illustrated comprises laminated core members 1, 2 and 3, the longitudinal axes of which are parallel and symmetrically disposed and which have the general form of square prisms. The four corners of each core member are similarly provided with notches 4 to fit a suitable-supporting frame.

Reactance coils 5, 6 and 7 are wound upon cylindrical spools 8, 9 and 10 which are fitted over the core members 1, 2 and 3, and the

several core members are of sufficient length to extend a short distance beyond the spools 55 at each end.

The positions of the spools upon the core members and the relative positions of the several core members are determined by a non-magnetizable frame structure which is 60 comprised of two similar triangular clamps 11 and 12. The triangular clamps are notched to engage the corners, and the notches 4, of the core members and have beveled edges to fit together. The beveled edges 65 of the clamps are bound together by suitable bolts 13 and the upper and lower clamps are fastened together by strips 14 which are parallel to the core members and are attached to the three sides of the triangular clamps near 70 their middle points in order to avoid interference with the spools on which the coils are wound. The three core members are further supported by spacing strips 15, which are fastened to the side strips of the triangular 75 clamps opposite the strips 14 and the ends of which are beveled to engage the inner corner notches of the core members. The triangular clamps 11 and 12, the connecting strips 14 and the spacing strips 15 are preferably 80 constructed of wood and are of such thickness that their surface is flush with the ends of the core members when they are attached thereto.

The core members 1, 2 and 3 are interconnected magnetically by laminated ring core members 16 and 17, that are constructed by winding magnetizable strap upon spools formed by center blocks 20 to which their disks 21 of non-magnetizable material are attached. The difference between the outer and inner radii of the rings is substantially equal to the width of the core members 1, 2 and 3 and the inside diameters are such that the ring core members are adapted to engage 95 the entire end surfaces of the core members. These rings serve to symmetrically distribute the flux, and the magnetic forces produced when the coils are energized tend to hold the ring against the ends of the other core members so that all the parts are readily held together by a relatively light frame structure and vibrations of the core are avoided.

The ring core members are held in position against the prismatic core members by tri-armed supports 18 which comprise an upper

and a lower bracket and are fastened together by a bolt 19 which passes through the center of the structure.

The inductance of the coils may be adjusted by loosening the bolt 19 and inserting non-magnetizable plates of suitable thickness between the ends of the cores 1, 2 and 3 and the ring members 16 and 17, thereby introducing a material air-gap in the magnetic circuit.

My invention is not confined to the arrangement shown but may readily be embodied in transformers or reactance structures having any number of coils, and I desire that variations in size and arrangement of details which do not depart from the spirit of my invention shall be included within its scope.

I claim as my invention:

1. The combination with core members, of coils wound on said members, magnetizable end rings which interconnect said core members, and a supporting frame of non-magnetizable material.

2. The combination with cylindrical coils, a core member for each coil, and magnetizable end rings, of a laminated structure for interconnecting said core members.

3. The combination with cylindrical coils, magnetizable cores therefor having longitudinal grooves and a non-magnetizable supporting frame for said members which is adapted to engage said grooves, of magnetizable end rings of laminated structure that are adapted to magnetically interconnect said core members.

4. The combination with three coils which are symmetrically disposed at the corners of a triangular non-magnetizable support, and interconnecting rings therefor, which are wound with magnetizable strap and which are adapted to engage the ends of said core members, of means for binding the several parts together.

5. The combination with end ring members of magnetizable material, prismatic core members of equal length that are located between the ring members, coils that are wound upon said core members and a frame of non-magnetizable material for maintaining a relative lateral position of the several parts, of means for holding the rings in position against the ends of the core members.

6. The combination with end ring members of magnetizable material, prismatic core

members of equal length that are located between the ring members, coils that are wound upon said core members and a frame of non-magnetizable material for maintaining a relative lateral position of the several parts, of means for holding the rings in position against the ends of the core members, that comprises an upper and a lower bracket and a bolt which passes through the center of the end rings and binds the two brackets together.

7. The combination with end ring members of magnetizable material, prismatic core members of equal length that are symmetrically disposed between the ring members, coils that are wound upon said core members and a frame of non-magnetizable material for maintaining a relative lateral position of the several parts, of means for holding the rings in position against the ends of the core members, that comprises an upper and a lower bracket and a bolt which passes through the center of the end rings and binds the two brackets together.

8. The combination with end ring members that are constructed of magnetizable strap and laminated prismatic core members of equal length that are symmetrically disposed between the ring members, of coils that are wound upon said core members and a frame of non-magnetizable material for maintaining a relative lateral position of the several parts.

9. The combination with end ring members that are constructed of magnetizable strap, laminated prismatic core members of equal length that are symmetrically disposed between the ring members, coils that are wound upon said core members and a frame of non-magnetizable material for maintaining a relative lateral position of the several parts, of means for holding the rings in position against the ends of the core members, that comprises an upper and a lower bracket and a bolt which passes through the center of the end rings and binds the two brackets together.

In testimony whereof, I have hereunto subscribed my name this 22nd day of March, 1906.

CHARLES LE G. FORTESCUE.
